Patented Sept. 24, 1918.

4 SHEETS—SHEET 4.

UNITED STATES PATENT OFFICE.

RAPHAEL JACOBUCCI, OF FALL RIVER, MASSACHUSETTS, ASSIGNOR OF ONE-HALF TO
HARRIS POLISNER, OF FALL RIVER, MASSACHUSETTS.

CARD-PRINTING PRESS.

1,279,701.

Specification of Letters Patent. Patented Sept. 24, 1918.

Application filed June 13, 1918. Serial No. 239,842.

To all whom it may concern:

Be it known that I, RAPHAEL JACOBUCCI, a citizen of the United States, residing at Fall River, in the county of Bristol and State of Massachusetts, have invented certain new and useful Improvements in Card-Printing Presses; and I do declare the following to be a full, clear, and exact description of the invention, such as will enable others skilled in the art to which it appertains to make and use the same.

The principal object of my invention is to provide a simply constructed and inexpensive, yet a highly efficient and durable press for printing and embossing business cards and the like; and with this general object in view the invention resides in the novel features of construction and unique combinations of parts to be hereinafter fully described and claimed, the descriptive matter being supplemented by the accompanying drawings which form a part of this specification and in which:

Figure 1 is a top plan view of the improved printing press;

Fig. 2 is substantially a central vertical longitudinal section thereof;

Fig. 3 is a vertical transverse section on the plane of the line 3—3 of Fig. 2 showing the type holder in operative relation with the platen;

Fig. 4 is a duplicate of Fig. 3 but showing the type holder in lowered position and illustrating the relative positions of the other moving parts when said holder is so lowered;

Fig. 5 is a side elevation of the platen;

Fig. 6 is a detail vertical section on the plane of the line 6—6 of Fig. 2; and,

Fig. 7 is a detail horizontal section on the plane of the line 7—7 of Fig. 2.

In the drawings above briefly described, the numeral 1 designates a supporting frame including a pair of substantially rectangular side members 2 each including an upper longitudinal bar 3 and a lower bar 4 parallel therewith. Having their lower ends secured to the longitudinal bars 3, are two end members 5 of arched formation as shown most clearly in Figs. 3 and 4, the crown bars 6 of said end members being disposed horizontally for a purpose to appear.

Extending between the end members 5 and contacting with the lower sides of the crown bars 6, is a longitudinally disposed

horizontal platen 7 having along its lower side a pair of card guiding ribs 8 and having at one end an inlet throat 9 into which the cards C are fed, said cards being deposited upon a sliding feed member 10 having an upstanding lip 11 which serves to feed said cards along the ribs 8 as said feed member is intermittently advanced, said feed member being returned to its initial position after each operation, so as to receive another card.

For operating the feed member 10, a lever 12 is shown fulcrumed at 13 upon the frame 1, the upper end of said lever having a pin and slot connection 14 with the slide, while a link 15 is pivoted to and extends from the lower end of said lever, this link being pivoted to a crank 16 on a short transverse shaft 17, said shaft being driven from a longitudinal drive shaft 18 by means of suitable beveled gears or the like 19. A pulley 20 and belt 21 or any other preferred means may be employed for driving the shaft 18 and although shaft 17 is shown carried rotatably by a bracket 22, any other preferred means could well be used for supporting this shaft.

By the operating means just described, the feed member 10 will be reciprocated so that the cards C will be fed along the platen 7 and guided in their movement by the ribs 8, each new card fed forwardly by the slide 10 serving to advance the other cards in the guideway as will be clear from Fig. 2.

A type holder 25 is located below the platen 7 and is rigidly carried by the front end of a transversely disposed lever 26 which is fulcrumed between its ends at 27 to a bracket 28 rising from the bar 3 of the rear side member 2, said holder being shown as carrying two sets of type 29 and 30 for printing upon the same card with differently colored ink, although it is to be understood that any suitable number of colors could be used and that the sets of type would correspond in number to the number of such colors. An embossing die 31 is also carried by the type holder 25, so that after printing of the cards with the several colors to be employed, they are finally embossed before being discharged into the outlet chute or hopper 32.

For operating lever 26 to raise the type holder 25 into operative relation with the platen 7, a preferably angular link 33 is piv-

oted at 34 to the rear end of said lever and at 35 said link is pivoted to a crank or eccentric 36 on the shaft 18. By this arrangement, when the crank has reached the position of Fig. 4, the type holder 25 will have been lowered to the maximum, whereas movement of the crank to the position indicated in Fig. 3, will have so pulled upon link 33 as to cause the lever 26 to raise the type holder into operative relation with the platen.

For inking the type 29 and 30, a pair of rollers 40 are shown mounted on a longitudinal rod 41 with which a forwardly and rearwardly moving frame 42 is provided, said frame having shoes 43 slidable along a pair of parallel tracks 44 which extend rearwardly from the type holder 25. The usual inking disks 45 coöperate with the rollers 40 and these disks may be slowly turned in any well known manner. It is necessary that the rollers 40 shall sweep over the type when the holder 26 is lowered and in order to obtain this result, the following construction is preferably employed.

Links 46 are pivoted to the rear end of frame 42 and also to the forked upper end 47 of a substantially vertical lever 48, said lever being fulcrumed at 49 to an extension 50 with which the bracket 28 is provided, the fulcrum being near the lower end of the lever as will be clear from Figs. 3 and 4. A link 51 is pivoted at 52 to the lower end of lever 48 and at 53, this link is pivoted to the first named link 33. By this arrangement, the one eccentric or crank 36 serves to not only operate link 33 to actuate the type holder 25 but operates also the link 51 which controls the action of the inking rollers 40.

In operation, the cards are fed by hand into the throat 9 of the platen 7 and are received upon the sliding feed member 10 as shown in Fig. 2. This member serves to intermittently feed the cards along the lower side of the platen and the several parts of the machine are so synchronized as to cause the type holder 25 to ascend during the period of rest of the feeding means. Each time the type holder rises, it prints in different colored ink upon the cards and at the same time embosses the card which was previously printed. The one machine thus performs the work at one operation heretofore requiring that the cards be fed several times through the press, thus effecting a great saving in time as well as labor. The machine is comparatively simple and inexpensive, yet it is obvious that it will be highly efficient and durable; and since probably the best results are obtained from the details shown and described, such details are by preference employed, but within the scope of the invention as claimed, numerous minor changes may well be made.

Particular emphasis is laid upon the fact

that the type holder 25 is located below the platen, since by this location, the working face of the type is exposed upwardly and may be much more easily cleaned than when facing downwardly as is the case with some printing presses. Other features which are important are the construction of the platen, and the novel arrangement of parts for operating the type holder and the inking means.

I claim:

1. A card printing press comprising a frame, a platen on said frame, guiding means for the cards extending along the lower side of said platen, means for intermittently feeding the cards along said guiding means, a lever fulcrumed on said frame and having a vertically moving end located below said platen, a type holder carried by said end of said lever, an eccentric, a link connecting said lever and said eccentric for operating the former to move said type holder toward said platen during the periods of rest of said feeding means, a proceeding and receding type inking device operatively associated with said type holder, an additional lever fulcrumed on the frame and operatively connected to said inking device, and an additional link connecting said additional lever with said first named link for operating the former to move said inking device across the type when said type holder is lowered.

2. A card printing press comprising a frame, a platen on said frame, guiding means for the cards extending along the lower side of said platen, means for intermittently feeding the cards along said guiding means, a lever fulcrumed on said frame and having a vertically moving end located below said platen, a type holder carried by said end of said lever, an eccentric, a link connecting said lever and said eccentric for operating the former to move said type holder toward said platen during the periods of rest of said feeding means, a pair of parallel tracks extending from said type holder, a type-inking device slidable along said tracks, an additional lever fulcrumed on the frame and connected to said inking device, and an additional link connecting said additional lever with said first named link for operating the former to move said inking device across the type when said type holder is lowered.

3. A card printing press comprising a frame including a pair of arched end members connected by a longitudinal bar at the rear of the frame, a longitudinal horizontal platen extending between and secured to the crowns of said arched end members, the lower side of said platen having means for guiding the cards along the same, a slide at one end of said platen for intermittently feeding the cards along said guiding means, means for actuating said slide, a bracket extending from the aforesaid longitudinal bar,

a transverse lever fulcrumed between its ends to said bracket and having its front end located below said platen, a type holder secured to said front end of said lever, an eccentric mounted on said frame, a link connecting the rear end of said lever with said eccentric, a proceeding and receding type inking device operatively associated with said type holder, an additional lever fulcrumed to said bracket and connected to said

inking device, and an additional link connecting said additional lever and said first named link.

In testimony whereof I have hereunto set my hand.

RAPHAEL JACOBUCCI.
